UNITED STATES PATENT OFFICE.

JOHANN J. DANIELS, OF NEW ROCHELLE, NEW YORK.

WINDOW-BLIND FASTENER.

No. 852,654.

Specification of Letters Patent.

Patented May 7, 1907.

Application filed November 21, 1906. Serial No. 344,408.

To all whom it may concern:

Be it known that I, JOHANN J. DANIELS, a subject of Germany, and a resident of New Rochelle, in the county of Westchester and State of New York, have invented certain new and useful Improvements in Window-Blind Fasteners, of which the following is a specification.

The invention relates to improvements in window-blind fastenings, and consists in the novel features, arrangements and combinations of parts hereinafter described and particularly pointed out in the claims.

The object of my invention is to provide a strong, neat looking and efficient window-blind fastening adapted to the limited space present between outside window-screens and blinds, said fastening to be capable of locking the blind in its closed position or in several partly open positions.

Various blind-fastenings adapted to windows having inside screens are well known but these are not, in my experience, adapted to windows having outside screens because of their construction and the limited space left between outside screens and blinds.

My invention resides in a fastening comprising an arm hinged at one end to a pin which is mounted in a vertical sleeve carried by a bracket secured to the blind, while at its other or free end said arm carries a pin which is adapted to a bracket carried by the blind near its free edge and also to any of a series of metal sockets embedded in the window sill at the outer side of the screen. The mounting of the fastening arm permits it to have a wide range of movement and enables it to be conveniently manipulated in operating the blind.

The invention will be fully understood from the detailed description hereinafter presented, reference being had to the accompanying drawings, in which:

Figure 1 is an elevation, partly broken away and partly in section, of a window frame equipped with window sashes, an outside screen and an outside blind and provided with blind fastening devices constructed in accordance with and embodying the invention; Fig. 2 is a vertical section of same on the dotted line 2—2 of Fig. 1; Fig. 3 is a horizontal section of same, partly broken away, on the dotted line 3—3 of Fig. 2, the blind being indicated by dotted lines in an open position; Fig. 4 is an enlarged detached vertical section through a portion of the blind, window-sill

and fastening devices on the dotted line 2—2 of Fig. 1; Fig. 5 is a vertical section indicating in detail the manner of fastening the hinged end of the fastening-arm to the blind, the section being on the dotted line 5—5 of Fig. 6, Fig. 6 is a horizontal section through a portion of the window blind and shows a top view, partly broken away, of the hinged end of the fastening-arm and the bracket supporting the same, and Figs. 7 and 8 are detached views, partly in section and partly broken away, illustrating the applicability of the fastening devices to blinds which open toward the right or toward the left, Fig. 8 illustrating the devices as applied to a blind to be pushed open toward the right and Fig. 7 indicating the same applied to a blind intended to be pushed open toward the left, the change from the blind opening toward the right to the one opening toward the left involving merely the reversal in position of the supporting bracket for the fastening arm.

In the drawings, 10 designates a window casing or framing of usual or any suitable construction, 11 the lower window sash, 12 the upper window sash, 13 the usual outside screen and 14 the blind, which is at the outside of the window and suitably secured by hinges 15 in a well known manner.

My invention relates to means for operating and fastening the window blind 14, and the means I have designed for this purpose are capable of being confined within the limited space permitted between said blind and the screen 13 and comprise an arm 16 which is at one end secured to the blind 14 and at the other end carries a pin which is adapted to be placed in engagement with any one of a series of sockets provided in the outer window sill when the blind is open and to engage a bracket carried by the blind and also one of said sockets when the blind is in its closed position.

Upon the lower portion of the inner side of the blind 14, near its hinged edge, I secure by means of screws a bracket 17 formed with a vertical sleeve 18, and this bracket I utilize for supporting the hinged end of the arm 16, which arm is a plain flat bar of metal secured at one end upon a pin 19 between the arms at the upper bifurcated end of the post 20 whose lower portion is of reduced diameter and constitutes a vertical pin 21 which passes through the sleeve 18 and is held therein by the head of a screw 22 which enters a socket in the lower end of said pin, as shown in Fig.

5, the head of the screw 22 being larger than the bore of the sleeve 18 and engaging the lower end of said pin 21 but not the lower edges of said sleeve. The upper portion of 10 the post 20 has a horizontal diameter about equal to the diameter of the sleeve 18 and bears upon the upper end of said sleeve. The post 20 cannot slip down through the sleeve 18 and the head of the screw 22 prevents said post from passing upwardly from 15 said sleeve. The pin 21 forming a part of the post 20 is free to turn axially within the sleeve 18, and the hinged end of the arm 16 is free to have a turning action upon the pin 19. The arm 16 is, at its hinged end, thus 20 carried by the blind 14 and is free to have a vertical hinge-movement upon the pin 19 and also a horizontal swiveling movement by reason of the mounting of the pin 21 within 25 the sleeve 18, this special mounting of the hinged end of the arm 16 being of special advantage in that it permits the arm 16 while being very firmly secured to have a wide range of movement and also enables 30 the operator to very conveniently actuate the blind, moving the latter inwardly or outwardly by direct pressure applied to the arm 16, this direct pressure being in this instance permitted from the fact that the arm may 35 be turned into the room when the window blind is closed and readily handled in pushing the blind to an open or a partly open position, as well as drawing the blind to its closed position.

35 The locking end of the arm 16 is provided with a vertical pin 23 which preferably extends both above and below said arm, as shown in Fig. 4, and is slightly tapered toward its ends. Upon the window blind, 40 near the lower edge of its inner side, I secure a bracket 24, which is simply an angle-plate provided in its horizontal member with a vertical opening 25 (Fig. 5) to receive the pin 23 when the blind is in its closed position 45 and also when said blind is in its full open position or thrown back against the wall, in which latter instance the bracket 24 serves merely as a support for the free end of the arm 16. When the pin 23 is in engagement 50 with the bracket 24 with the blind in its closed position, said pin passes entirely through said bracket and enters a metal socket 26 seated within the window sill directly below said bracket, as shown in Fig. 54, and in this use of the bracket, the latter being in near relation to the upper end of said socket, it serves to aid in securely locking the blind in its closed position.

55 I provide the window-sill with a series of 60 metal sockets 26 (all sunk into the sill) to receive the lower end of the pin 23 with the blind 14 in the partly open positions in which it may be desired to place the same, said pin being adapted to any of said sockets. The 65 socket 26 which is directly below the bracket

24 when the window is closed, may also be utilized to receive the lower end of the pin 23 when the blind is in a partly open position, as I illustrate by dotted lines in Fig. 3.

The special mounting of the hinged end of 70 the arm 16 enables said arm to be turned upwardly at an angle and moved horizontally into the room when the blind is in closed position or to be turned completely upside-down when, for illustration, the blind is in, 75 say, the position shown by dotted lines in Fig. 3, and it may be desired to lock the arm 16 in the bracket 24 and shove the blind to its full open position against the side of the wall. When the blind is in its full open position 80 against the side of a wall, the arm 16 may be grasped near its hinged end and again turned upside-down or reversed preparatory to drawing the blind inwardly to its closed position. The arm 16 is thus capable of a very wide range of movement and affords great convenience in operating the blind. The fact that the arm 16 when turned upwardly at an angle may also have a swiveling motion with the pin 21, without 85 binding against the sleeve 18, is also of advantage. It is advantageous also that the pin 21 has an extended vertical bearing within the sleeve 18, since thereby firmness of construction and ease and regularity of 90 movement are secured.

95 Preferably I extend the pin 23 above and below the arm 16 so that said arm may during its manipulation in the operation of the blind, be turned upside-down or reversed in 100 the manner hereinbefore indicated, and this provision of the double-ended pin 23 also enables the ready use of the arm 16 for either right or left hand blinds. I do not, however, limit my invention in every instance to the 105 extending of the pin 23 above and below the arm 16.

When it is desired that the fastening devices, as manufactured, may be equally applicable to blinds which open toward the 110 right and those which open toward the left, the sleeve 18 should occupy a central position between the upper and lower edges of the bracket 17, as shown in Figs. 7 and 8, since thereby when the said bracket is turned 115 upside-down to reverse its position in adapting it for use on, for instance, a left-hand blind, as shown in Fig. 7, from its arrangement for a right-hand blind shown in Fig. 8, the upper end of the post 20 may be maintained at its predetermined height. If the bracket 17 in the construction shown in Fig. 5 were reversed to adapt the fastening devices for a blind opening toward the left, the upper end of the post 20 would project un- 120 duly above the then upper edge of the bracket 17, due to the fact that the sleeve 18 in Fig. 5 is not disposed equally between the upper and lower edges of the bracket. It may therefore be preferred in the construc- 130

tion of the bracket 17 to locate the sleeve 18 centrally between the upper and lower edges of the same.

The fastening devices of my invention are not only advantageous in construction but are neat in appearance and adapted to the limited space present between outside-screens and blinds.

What I claim as my invention and desire to secure by Letters-Patent, is:

1. A window-blind fastening comprising a securing arm having a locking-pin at its free end, an apertured bracket secured to the blind and adapted to receive said pin, a bracket secured to the blind near its hinged edge and affording a vertical bearing, a vertical post engaging said bearing and adapted to have an axial movement, and means hinging said arm to said post, said locking-pin being adapted to engage sockets to be provided in the window-sill; substantially as set forth.

2. A window-blind fastening comprising a securing arm having at its free end a locking-pin projected above and below the arm, an apertured bracket secured to the blind and adapted to receive said pin, a bracket secured to the blind near its hinged edge and affording a vertical bearing, a vertical post engaging said bearing and adapted to have an axial movement, and means hinging said arm to said post and permitting it to be turned over upside down when required, said locking-pin being adapted to engage sockets to be provided in the window-sill; substantially as set forth.

3. A window-blind fastening comprising a securing arm having a locking-pin at its free end, an apertured bracket secured to the blind and adapted to receive said pin, a bracket secured to the blind near its hinged edge and affording a vertical sleeve bearing, a vertical post mounted to have an axial movement in said bearing and having a bifurcated upper end, and a pin hinging said arm between the members at the upper end of said post, said locking pin being adapted to engage sockets to be provided in the window-sill; substantially as set forth.

4. A window-blind fastening comprising a securing arm having a locking-pin at its free end, an apertured bracket secured to the blind and adapted to receive said pin, a bracket secured to the blind near its hinged edge and affording a vertical sleeve bearing, a vertical post mounted to turn axially in said bearing, a headed screw entering a socket in the lower end of said post for securing the same freely within said bearing, and a pin securing said arm in a hinged manner to the upper end of said post, said locking pin being adapted to engage sockets to be provided in the window-sill; substantially as set forth.

Signed at New York city, in the county of New York and State of New York, this 17th day of November A. D. 1906.

JOHANN J. DANIELS.
